SINK OR THE LIKE

Bernard R. Kanoff, 1002 E. Phil-Ellena St.,
Philadelphia, Pa.

Filed May 4, 1961, Ser. No. 65,022

Term of patent 14 years

(Cl. D4—2)

Fig. 1

Fig. 2

Fig. 3

The dominant features of my design reside in the part shown in solid lines.

I claim:

The ornamental design for a sink or the like, as shown and described.
